DISBARKING MACHINE

Karl Gustaf Hellner, Nalden, Sweden, assignor
of one-half to Axel Gustaf Johansson, Nalden,
Sweden

Application March 10, 1931, Serial No. 521,606
In Sweden April 3, 1930

14 Claims. (Cl. 144—208)

The present invention relates to a disbarking machine for parallel stripping according to the tumbling principle, that is to say in such a manner that the logs or parts of logs to be stripped are kept enclosed within a rotatable drum in intimate contact with each other, and parallel to the axis of the drum, the logs being caused by tumbling to rub against each other, if desired in the presence of water, so that the bark is stripped off.

10 The feature of the invention is based on the utilization of the known fact that, when a plurality of logs are in this manner enclosed within a rotating disbarking drum, that the logs which are situated on that side of the axis of the drum where the wall of the drum moves upwardly, will be piled up along that wall of the drum or by carriers secured thereto, so that the thus piled up logs will be situated higher than the logs which are situated on the opposite side of the axis of the drum where the wall of the drum moves downwardly.

15 These circumstances are utilized, according to the invention, inter alia to bring about automatic emptying of the drum, that is to say for removal of entirely or partly stripped logs from the drum, without the latter having to be provided with a cover and without it being necessary to stop the same.

20 The arrangement aimed at by the invention is principally characterized by the feature that the disbarking drum has one or more openings extending preferably along the whole of its length, and by the provision outside the drum of one or more members in such a manner that, when the opening of the drum, or any of the openings thereof, have, during the rotation of the drum, been brought right opposite the uppermost log or logs which, while enclosed in the drum, have been brought upwardly by the latter, the said log or logs may fall out through the opening without being prevented by the member or members, partly enclosing the drum, whereas said member or members will otherwise prevent the logs from falling out.

25 The arrangement may be carried out by means of various embodiments either for periodic disbarking, that is to say in such manner that the disbarking drum is first filled and then driven round until disbarking of all logs has been finished; or, the disbarking operation may take place continuously in such manner that the logs are successively fed in during operation, and are also delivered during operation in a disbarked or partly disbarked state.

The accompanying drawing illustrates a few embodiments of the invention by way of example. Fig. 1 is a longitudinal section of a disbarking drum arranged according to the invention, and Fig. 2 shows the drum in cross section. Fig. 3 is a cross section of two disbarking drums arranged in series and adapted for continuous disbarking. Fig. 4 is a diagrammatic view showing a modified embodiment of the members surrounding the drum and Fig. 5 is a transverse section of another form of the invention.

30 According to Fig. 1 the disbarking drum comprises two plane side walls 1 carried by the shaft 2 or by journals secured to the side walls. The shaft is rotatably mounted in the bearings 3 and 4 may be protected by a sleeve 4 against blows and shocks from the logs to be disbarked. Motive power is transmitted to the shaft through the toothed wheel 5 or some other suitable transmission means. Between the side walls 1 and 5 secured to their circumferences are U-irons having intermediate spaces between them to permit passage of the bark. These U-irons reinforce the wall of the drum preferably composed of plates 6 secured between the side plates, as shown in the drawing, said plates being provided with carriers 7 on the inside, if desired. The wall of the drum has one or more openings 8 extending between the side plates, according to Figs. 1 and 2 of the drawing. The drum rotates in known manner in a tub 10. 9 is a conveyor by means of which the logs are conveyed to and delivered into the drum.

35 Secured outside the drum in the tub 10 are retaining slide bars 11 or plates concentric with the drum, said slide bars or plates preventing the logs enclosed within the drum from falling out through the openings 8 when they are situated inside or next above the extension of the tub 10 concentric with the drum. Attached between the bars 11 on the outside of the drum are carriers 12 which extend into the spaces between the bars 11 (see Fig. 1), so as to carry the logs with them, when the latter project from the openings 8 while these are directed downwardly, and so as to entrain the bark projecting into the spaces between the bars 11.

40 On that side of the drum where the wall thereof moves upwardly, the bars 11 are extended in an upward direction beyond the highest point to which the logs are carried by the drum. The said bar extensions are pivoted at 21, so that they may be turned outwardly in the lateral direction, that is to say to the right according to Fig. 2. The arrangement above described is used and operates in the following manner.

45 When the drum is to be filled, it is kept stationary.

ary with one of the openings 8 in the approximate position relatively to the conveyor 9 shown in Fig. 2. The logs may then, according as they are delivered by the conveyor fall from the latter down into the drum through the opening 8. The upper pivoted extensions of the bars 11 are kept in the upright position. When the drum has been filled with the proper number of logs it is rotated in the direction of the arrow 22. The enclosed lot of logs then takes the position represented in Fig. 3. During the rotation none of the logs can fall out of the drum, whether the drum openings 8 be directed downwardly or obliquely upwards. The falling out of the same in the downward direction is prevented by the bars 11 as hereinbefore described, and, when one of the openings is directed obliquely upwards to the right, the logs are prevented from falling out by the upright extensions of the bars 11, whereas, when any of the openings 8 is directed obliquely upwards to the left, the falling out of the logs is obviously out of the question, inasmuch as the lot of logs is then entirely removed from the opening (see Fig. 3).

Emptying of the drum upon completed disbar-
ing is simply effected by the pivoted extensions of
the bars 11 being turned down to the right (Fig. 2)
while the drum continues to rotate. When any
of the drum openings 8 is then brought above
the fixed bars, that is to say above the pivots 21
of the bar extensions, the logs carried upwardly
by the drum are caused to fall out through the
opening. In this manner emptying takes place
each time an opening 8 is brought above said
pivot 21.

The bars 11 may also be made rigid along the
whole of their length, that is to say, their upper
extensions need not be pivoted. In this case the
drum is emptied by being rotated in the direction
opposite to that during the disbaring operation,
logs then falling out each time an opening 8 is
brought above the upper ends of the bars shown
to the left in Fig. 2.

The arrangement shown in Fig. 3 for con-
tinuous disbaring operates substantially in the
manner above described. The disbaring drums
arranged in series are then provided, each per-
se, with one or more openings 13 and 14 respec-
tively. Secured to the drum tubs are bars 18 and
23 respectively, these bars extending for the
major portion of their length along the lower
part of the drums in question. The drums are
surrounded by bars 17 and 20 rigidly connected
therewith, said bars being interrupted at the
points corresponding to the drum openings 13
and 14. The logs are delivered by the con-
veyor 15 which is connected to the rigid bars
18 through the inclined board 16. From the
highermost point of the bars 18, to the right ac-
cording to the drawing, the inclined board 19
extends down to the highermost left point of the
rigid bars 23. From the highermost point of
the bars 23 on the right hand side, the inclined
board 24 extends down to the conveyor 25.

The arrangement last described operates in
the following manner.

The logs carried by the conveyor 15 are de-
livered onto the board 16 and are guided down-
wardly by the latter so as to bear against the
bars 17 of the first drum. When the bar inter-
ruption and the drum opening corresponding
thereto have been brought level with the board
16, the logs fall into the drum. When the opening
13 gets above the highermost point of the
bars 18 on the right hand side, the logs carried

along upwardly to the highest point fall out onto
the board 19, are guided by the latter downwardly
to bear against the bars 20 of the next drum,
after which they will fall into the drum when
the interruption of said bars and the drum
opening corresponding thereto have been brought
down to the upper edge of the board 19, and
when the opening 14 has been brought above the
board 24, the said logs fall out onto the latter
which guides the logs down onto the conveyor
25. In this manner, more than two disbaring
drums may evidently be arranged in series. The
opening or openings 13 of the drum situated first
in the series are arranged in their position of
rotation relatively to the opening or openings
14 of the following drum, in such a manner
that the opening 13 passes the unloading ends of
the bars 18, immediately before the opening 14
is brought level with the slide board 19. By
this means, logs that have fallen out onto the
slide board 19 will remain lying on the board 19
for as short a period of time as possible, thus
causing the least possible sliding resistance
against the bars 20.

The bars 17 and 20 rigidly connected with the
drums may be dispensed with, if desired, and in-
stead the logs guided downwardly by the boards
16 and 19 will bear directly against the walls of
the drums, if this is permitted by the construc-
tion and the resistance of the drum walls.

In the embodiment according to Fig. 4, the
bars 11, and 18 and 23 respectively, which ac-
cording to the description hereinbefore are rigid-
ly connected with the drum tub or the drum
tubs respectively, are replaced by chains 26 run-
ning over rollers 27. When the logs then project
through the drum opening 27' during the rota-
tion of the drum while the drum opening is di-
rected downwardly, the chains 26 are carried
along, that is to say, the logs do not slide against
the parts surrounding the drum. In this manner
the frictional resistance produced when the sur-
rounding parts consist of rigid bars according
to Figs. 1-3, is neutralized.

If for some reason or other the drum would
suddenly stop during the disbaring operation
when the drum opening occupies the position
shown on the left in Fig. 3, the logs then hav-
ing the most elevated position in the drum could
fall out through the opening. To prevent this,
a shutter 28 is provided outside the drum as an
extension of the fixed surrounding of the drum,
as shown in Fig. 5, said shutter being carried by
arms 29 swingably mounted about a fixed point
30. As will be seen from Fig. 5, this shutter will
prevent the logs from falling out through the
drum opening 13. The arrangement of the shut-
ter also involves the advantage that the point
31 of the fixed surrounding of the drum over
which the logs may fall out of the drum when
the latter is rotated in a reversed direction, in
the manner stated hereinbefore, may be located
considerably farther down than when there is no
shutter 28. When the drum arranged according
to Fig. 5 is to be emptied, the shutter 28 is swung
up so that its upper edge is caused to bear against
the fixed part 32. The drum opening is then
free, and when the drum is rotated clockwise,
the logs will fall out easily and quickly through
the opening.

During the disbaring the drum in Fig. 5 ro-
tates in a counter-clockwise direction. When it
is desired to empty this drum the same is rotated
in a clockwise direction after the shutter 28 has
been raised in any suitable manner.

What I claim is:—

1. A disbarking machine for parallel stripping on the tumbling principle, comprising a rotating disbarking drum provided with at least one side opening extending approximately along the whole of its length, and at least one retaining part arranged independently of and in close relation to the outside of the drum to prevent the logs enclosed within the drum from falling out through the opening when the latter move along said part during the rotation of the drum. 80
2. A disbarking machine according to claim 1, wherein the retaining part includes an independent adjustable section movable into a position which permits the logs to fall out of the drum while the latter is rotating. 85
3. A disbarking machine for parallel stripping on the tumbling principle comprising a trough, a disbarking drum rotatably mounted in the trough and provided with at least one opening extending approximately throughout the length of the drum, retaining means arranged transversely of the trough and in close relation to the outer surface of the lowermost portion of the drum to prevent the logs from falling through the opening in the drum during rotation thereof. 90
4. A disbarking machine according to claim 1, wherein the retaining part consists of a bar concentric with the drum and arranged adjacent the lower side of the drum along a portion of its length. 95
5. A disbarking machine according to claim 3, wherein the retaining means includes a bar partly enclosing the drum secured in the trough in which the drum rotates. 100
6. A disbarking machine according to claim 3, wherein the retaining means is in the form of a bar arranged adjacent the lower portion of the drum and extended upwardly above the axis of rotation of the drum, on that side of said axis where the wall of the drum moves upwardly during the disbarking process. 105
7. A disbarking machine according to claim 1, wherein the retaining part includes an adjustable extension pivotally supported on that side, where the wall of the drum moves upwardly during the disbarking process, the said extension being adapted to be turned outwardly at a point approximately level with the axis of the drum. 110
8. A disbarking machine according to claim 3, wherein the retaining means include a plurality of spaced bars and wherein carriers are provided on the outside of the drum and entering axial spaces provided between the bars in order to carry the logs projecting from the drum opening against the bars, and also to remove bark accumulating in said spaces. 115
9. A disbarking machine according to claim 1, wherein rigid extensions are provided on the retaining part on that side where the wall of the drum moves upwardly during the disbarking process, the end of the part opposite to the rigid extension being situated on so low a level relatively to the axis of the drum that the latter may be emptied over the last-mentioned part by a reversal of the direction of rotation. 120
10. A disbarking machine according to claim 3, wherein a supporting shaft is provided for the drum and extends lengthwise through the drum, and a pipe surrounding the shaft and serving to protect the shaft against shocks from the logs enclosed within the drum. 125
11. A disbarking machine according to claim 1, wherein the retaining part consists of rollers, and chains running over the rollers and guided along the lowermost portion of the drum. 130
12. A disbarking machine according to claim 1, wherein a fixed part is provided partly enclosing the drum on that side where the drum moves counter-clockwise during the disbarking process and wherein a shutter is provided and is swingably mounted substantially concentrically of the drum, said shutter forming a continuation of the fixed part and the peripheral extension of the shutter being such that the same will cover the drum opening when moving counter-clockwise. 135
13. A disbarking machine for parallel stripping on the tumbling principle, comprising a receptacle, a disbarking drum rotatable therein and provided with at least one opening extending approximately throughout its length, retaining bars fixed transversely of the receptacle and arranged to engage the lower portion of the drum so as to prevent the logs enclosed within the drum from falling out through the opening when the latter move along said part during the rotation of the drum, a slide board connected with the retaining bars on one side of the drum, means for delivering logs to said slide board, another slide board on the opposite side of the drum, and other bars rigid with the drum with interruptions corresponding to the drum opening, said last named bars cooperating with the first slide board so that the logs when moving down said slide board will rest against the bars on the drums until the interruptions are brought level with the slide board. 140
14. A disbarking machine in accordance with claim 13, wherein a plurality of drums are provided between a plurality of the slide boards. 145

KARL GUSTAF HELLNER.
